[57] CLAIM

The ornamental design for an aerosol dispenser, as shown and described.

DESCRIPTION

FIG. 1 is a perspective view from the back, above, and to one side of an aerosol dispenser showing the new design;

FIG. 2 is a back elevational view of the aerosol dispenser of FIG. 1;

FIG. 3 is a left side elevational view of the aerosol dispenser of FIG. 1, the right side elevational view being a mirror image thereof;

FIG. 4 is a top plan view of the aerosol dispenser of FIG. 1; and,

FIG. 5 is a front elevational view of the aerosol dispenser of FIG. 1.

The bottom and interior of the dispenser form no part of the claimed design.
